UNITED STATES PATENT OFFICE

2,050,135

ELECTRICAL CIRCUITS FOR
GAS-DISCHARGE TUBES

Reuben S. Tour, Cincinnati, Ohio

Application September 7, 1933, Serial No. 688,471

13 Claims. (Cl. 175—320)

My invention relates to an improved combination of electrical circuits for a plurality of gaseous-discharge tubes, where a continuous parallel, or predetermined sequential intermittent discharge of selected tubes is desired.

The principal object of the present invention is to make possible the selective operation, continuously or intermittently in predetermined sequence, of any or several of a plurality of gaseous-discharge tubes, connected in parallel to a single source of power supply, said tubes serving for illumination, for advertising, or for operation of electrical relays or similar devices.

Other objects of my invention will appear from the detailed descriptions of specific applications hereinafter contained.

The present art of using gaseous-discharge tubes normally requires that each tube be connected across an individual source of power which must necessarily be of sufficiently high voltage to break down, discharge, or ionize the gas in the tube although such voltage is much higher than is necessary to maintain current flow through the tube when once the tube has been discharged. The voltage characteristic of gaseous discharge tubes, which requires high voltage for breakdown or starting followed by a much lower voltage for maintaining current flow, makes impractical under existing systems, the parallel operation of a plurality of tubes on one source of power. Except by the use of expensive auxiliary apparatus, the discharge of one tube immediately reduces the applied voltage on the others; or if a constant voltage transformer is used, the discharged tubes will be much overloaded. This voltage characteristic of gaseous discharge tubes not only requires individual sources of power for each tube in operation, but requires further that these sources have current limiting properties.

Gaseous-discharge tubes may be ionized or discharged by applying across them a voltage surge or an alternating voltage of steep wave front such as is characteristic of high frequency alternating potentials. Once discharged by such high frequency wave front, the tubes may be supplied current from some other suitable power source of proper voltage for the discharged tubes.

The high frequency alternating potentials or voltage surges with steep wave fronts may originate from any suitable source, the power required being negligible. A sparking device as is shown in these specifications is ordinarily the most simple and effective source of voltage surges, but is not necessarily the only possible source.

Since the energy required in the high frequency

circuits is exceedingly small and since the power carried through the tube may be comparatively large, this method of operating gaseous discharge tubes lends itself admirably to the motivation of electrical relays or similar devices. Thus, if a spark of negligible energy be caused to occur in the high frequency circuit of any chosen tube, that tube is ionized and can pass a large current through any series connected relay solenoid. In this way a series of relays or a multiple point relay may be operated in any specified sequence. Or, if desired, the spark or other high frequency source may be maintained in continuous operation external to the respective high frequency circuits of any of the tubes, connection being made to impress the continuously available train of voltage surges across any desired tube or tubes at any desired time, thus operating the relay or other device. Both the above systems are shown for relay operation in the drawings, 20 wherein:

Figure 1 is a diagram of the new system of circuits as employed for the operation of an "on-and-off" relay, using one gaseous discharge tube for the "on" position and another for the "off" position.

Figure 2 is a diagram of the new system of circuits as employed for the operation of a multiple point relay or other device requiring the use of a plurality of gaseous-discharge tubes and depending on the selective discharge of one or several of said tubes.

Figure 3 is a diagram of the new system of circuits as simplified for operating a plurality of gaseous-discharge tubes in an illuminated sign, 35 where the sequence of operation of the respective tubes may be predetermined.

Figure 4 is a modification of Figure 3.

Figure 5 is a diagram of the new system of circuits as further simplified and applied broadly 40 to the continuous operation of gaseous-discharge tubes in parallel.

Referring to Figure 1, the numerals 1 and 2 indicate gaseous-discharge tubes each series-connected with one of the relay coils 3 and 4 of an "on-and-off" relay. The series couplets of tube and coil are connected in parallel across coil 5 of a transformer energized by line circuit 6. The potential of transformer 5 is insufficient to discharge tubes 1 or 2, but if an ionizing voltage 50 surge be imposed across either tube, its resistance will then be so lowered as to permit current to flow from transformer 5 through that tube and its relay coil 3 or 4, which respectively operate external circuit controlling devices, not shown. 55

The voltage surges necessary for ionizing tubes 1 and 2 are respectively available from spark gaps 7-9 or 8-9, sparking terminals 7 and 8 being supplied high potential by transformer 10 to which they are connected in parallel through separating chokes 11 and 12. Transformer 10 is energized by any commercial or low frequency source of power and supplies high potential to terminals 7 and 8 respectively through controlling switches 13 and 14, and condensers 15 and 16, the latter serving to limit the energy in the spark and prevent destructive arcing. The return circuit for the high potential spark discharge from common sparking terminal 9, which is preferably the needle of a galvanometer, adapted as described in my Patent No. 1,962,849, of June 12, 1934; is connected to the common terminal of tubes 1 and 2 by means of a wire 75 in the meter, and external leads. A spark discharge at 7 or 8 sets up also a high frequency voltage surge which is imposed across tubes 1 or 2 respectively through condensers 17 or 18, which also serve as charging condensers across high potential winding 10. The connections of condensers 17 and 18 to the tubes are separated by relay coils 3 and 4 now acting as chokes to permit building up of a surge potential across the individual tubes. Tube 1 is thus in a high frequency circuit through 17, 13, 15 with terminal 7 which sparks when desired to terminal 9 connected to the other side of the tube through wire 71. Likewise tube 2 is in a high frequency circuit through 18, 14, 16 with terminal 8 which sparks to terminal 9 when desired, and wire 71. The switches 13 and 14 may be manually or mechanically controlled by any suitable means or may be operated by the relay solenoid coils 3 and 4 in alternating sequence. For such operation the switch arms are mechanically connected together by means of a link 76, so that when solenoid 3, for instance, is energized to open switch 13, switch 14 is automatically closed and ready so that a high frequency circuit will be completed through tube 2 by movement of the galvanometer needle 9 into sparking relation with spark terminal 8. When such spark occurs the solenoid 4 is energized by the low potential circuit from transformer 5 through tube 2 which is ionized by the generated high frequency at the spark gap. The arm of switch 14 is accordingly moved to open the circuit of terminal 8 and close that of terminal 7 for actuation on the reverse movement of the needle 9.

In Figure 2 the new system of circuits has been shown expanded and adapted for the operation of a plurality of gaseous discharge tubes 20, 21, 22, and 23 serving to operate a multiple point relay or other similar device. Each of said tubes is series connected, with one of the solenoid coils 24, 25, 26, 27 of the relay, the couplets of tube and coil so formed being connected in parallel across the low potential, low frequency transformer 28, energized by line circuit 29. The gas tubes, exclusive of their series coils, are respectively connected by condensers 30, 31, 32, 33 into individual high frequency circuits. The said high frequency circuits are in turn connected in parallel through switches 34, 35, 36, 37 to one terminal of a high frequency source, such as spark gap 38, the other terminal of which is connected to the common terminals of the tubes. The high frequency circuits are supplied high potential low frequency current for sparking across gap 38 by transformer coil 39 through choke coils 40, 41, 42 and 43, with condensers 30, 31, 32, and 33 serving as charging condensers. A condenser 44 may

be used if necessary as a current limiting impedance to prevent destructive arcing at gap 38. The controlled operation of the switches 34, 35, 36 and 37 ionizes the respective tubes permitting the flow of low potential current through the 5 respective series connected relay coils 24, 25, 26 and 27 whereby the relay is operated.

In Figure 3 the new system of circuits as shown in the above figures is simplified for use in illuminated sign advertising, while Figure 4 is a modification of Figure 3. In Figures 3 and 4, a plurality of gaseous-discharge tubes 45, 46, 47 and 48 are connected in parallel across the transformer coil 49, high frequency chokes 50, 51, 52 and 53 being inserted, one to a tube, into one connecting lead of each tube. High potential low frequency transformer 54 charges condenser 55 and supplies energy to the sparking device 56 through the optional current limiting impedance 57, the latter to prevent destructive arcing. The high frequency generated by the spark surges is directed by switches 58, 59, 60, 61 respectively to gaseous-discharge tubes 45, 46, 47 and 48, while choke 62 prevents sparking at the switch points. Choke 63 prevents high frequency currents shorting around the tubes through the transformers, forcing said currents through condenser 55 and the selector switches. In Figure 4 chokes 62 and 63 are combined.

In Figure 5 the new system of circuits is further simplified for use in the continuous and simultaneous operation of a plurality of gaseous-discharge tubes 63, 64, 65 and 66 connected in parallel across a low potential transformer coil 67. The high potential low frequency circuit of transformer coil 68 charges condenser 69 and supplies energy to the spark 70 through current limiting impedance 71. The high frequency surges from the sparking at 70 are imposed across tubes 63, 64, 65 and 66 being constrained by choke 72 from shorting around the tubes. The said tubes are therefore kept in a state of apparently continuous illumination or discharge by the alternating low potential current supplied from transformer coil 67.

Having thus fully described my invention what I claim as new and desire to secure by Letters Patent is:

1. A system of electrical circuits for the simultaneous discharge of a plurality of cold cathode gaseous-discharge tubes, said system comprising a plurality of said tubes connected in parallel across a power source of lower potential than required to ionize the said tubes, a high frequency choke series connected between said plurality of tubes and said low potential source, a high frequency power source, and means for continuously impressing said high frequency across the electrodes of said gaseous-discharge tubes whereby said tubes are ionized on each half cycle of alternating potential and their resistance so lowered as to permit completion of the low potential circuit through said tubes.

2. A system of electrical circuits for the simultaneous discharge of a plurality of cold cathode gaseous-discharge tubes, said system comprising a plurality of said tubes connected in parallel across a power source of lower potential than required to ionize the said tubes, a high frequency choke series connected between said plurality of tubes and said low potential source, a high potential circuit, a sparking device in said high potential circuit for generating high frequency oscillations, and circuits for continuously impressing said oscillations across the electrodes 75

of said gaseous-discharge tubes whereby said tubes are ionized on each half cycle of alternating potential and their resistance so lowered as to permit completion of the low potential circuit through said tubes.

3. A system of electrical circuits for the selective discharge of a predetermined tube or tubes among a plurality of cold cathode gaseous-discharge tubes, said system comprising a plurality of said tubes, a like plurality of choke coils each series connected with one of said tubes to form a couplet, the plurality of couplets so formed being connected in parallel across a power source of lower potential than required to ionize the tubes, a power source to supply high frequency oscillations, choke coils to prevent shunting the high frequency oscillations around the tubes, condensers for coupling the high frequency oscillations to the respective tubes, and circuits for selectively and continuously impressing said high frequency oscillations across the electrodes of predetermined gaseous-discharge tubes whereby said tubes are ionized on each half cycle of alternating potential and their resistance so lowered as to permit completion of the low potential circuit through the selected tubes and the connected coils.

4. A system of electrical circuits for the selective discharge of a predetermined tube or tubes among a plurality of cold cathode gaseous-discharge tubes, said system comprising a plurality of said tubes, a like plurality of choke coils each series connected with one of said tubes to form a couplet, the plurality of couplets so formed being connected in parallel across a power source of lower potential than required to ionize the tubes, a plurality of high frequency circuits for impressing ionizing oscillations across the electrodes of said tubes, one of said tubes exclusive of its choke coil being connected in series in each of said high frequency circuits, a power source to supply high frequency oscillations choke coils to prevent shunting the high frequency surges around the tubes and means for selectively and continuously transmitting said high frequency oscillations to predetermined high frequency circuits to ionize and so lower the resistance of their respectively included gaseous-discharge tubes as to permit completion of the low potential circuit through the selected tubes and the connected coils.

5. A system of electrical circuits for the selective discharge of a predetermined tube or tubes among a plurality of cold cathode gaseous-discharge tubes, said system comprising a plurality of said tubes, a like plurality of choke coils each series connected with one of said tubes to form a couplet, the plurality of couplets so formed being connected in parallel across a power source of lower potential than required to ionize the tubes, a plurality of high frequency circuits for impressing ionizing oscillations across the electrodes of said tubes, one of said tubes exclusive of its choke coil being connected in series in each of said high frequency circuits, a power source to supply high frequency oscillations, choke coils to prevent shunting the high frequency oscillations around the tubes, condensers for coupling the high frequency oscillations to the respective tubes, and means for selectively and continuously transmitting said high frequency oscillations to predetermined high frequency circuits to ionize and so lower the resistance of their respectively included gaseous-discharge tubes as to permit completion of the low potential circuit through the selected tubes and the connected coils.

6. A system of electrical circuits for the selec-

tive discharge of a predetermined tube or tubes among a plurality of cold-cathode gaseous-discharge tubes, said system comprising a plurality of said tubes, a like plurality of choke coils each series connected with one of said tubes to form a couplet, the plurality of couplets so formed being connected in parallel across a power source of lower potential than required to ionize the tubes, a high potential circuit, a sparking device in said high potential circuit for generating high frequency oscillations, and circuits for selectively and continuously impressing said high frequency oscillations across the electrodes of predetermined gaseous-discharge tubes whereby said tubes are ionized and their resistance so lowered as to permit completion of the low potential circuit through the selected tubes and the connected coils.

7. A system of electrical circuits for the selective discharge of a predetermined tube or tubes among a plurality of cold cathode gaseous-discharge tubes, said system comprising a plurality of said tubes, a like plurality of choke coils each series connected with one of said tubes to form a couplet, the plurality of couplets so formed being connected in parallel across a power source of lower potential than required to ionize the tubes, a high potential circuit, a sparking device in said high potential circuit for generating high frequency oscillations, choke coils to prevent shunting the high frequency oscillations around the tubes, condensers for coupling the high frequency oscillations to the respective tubes, and circuits for selectively and continuously impressing said high frequency oscillations across the electrodes of predetermined gaseous-discharge tubes whereby said tubes are ionized and their resistance so lowered as to permit completion of the low potential circuit through the selected tubes and the connected coils.

8. A system of electrical circuits for the selective discharge of a predetermined tube or tubes among a plurality of cold cathode gaseous-discharge tubes, said system comprising a plurality of said tubes, a like plurality of choke coils each series connected with one of said tubes to form a couplet, the plurality of couplets so formed being connected in parallel across a power source of lower potential than required to ionize the tubes, a plurality of high frequency circuits for impressing ionizing oscillations across said tubes, one of said tubes exclusive of its choke coil being connected in series in each of said high frequency circuits, a high potential circuit, a sparking device in said high potential circuit for generating high frequency oscillations, choke coils to prevent shunting the high frequency oscillations around the tubes, condensers for coupling the high frequency oscillations to the respective tubes, and means for selectively and continuously transmitting said high frequency oscillations to predetermined high frequency circuits to ionize and so lower the resistance of their respectively included gaseous-discharge tubes as to permit the completion of the low potential circuit through the selected tubes and the connected coils.

9. A system of electrical circuits for the selective discharge of a predetermined tube or tubes among a plurality of cold cathode gaseous-discharge tubes, said system comprising a plurality of said tubes, a like plurality of choke coils each series connected with one of said tubes to form a couplet, the plurality of couplets so formed being connected in parallel across a power source

of lower potential than required to ionize the tubes, a plurality of high frequency circuits for impressing ionizing oscillations across said tubes, one of said tubes exclusive of its choke coil being connected in series in each of said high frequency circuits, a high potential circuit to supply energy to the said high frequency circuits, a sparking device for generating high frequency oscillations and a switch in each of said high frequency circuits, choke coils to prevent shunting the high frequency oscillations around the tubes, condensers for coupling said high frequency oscillations to the respective tubes, and means for selectively operating said switches to cause 10 sparking and continuous high frequency oscillations in predetermined high frequency circuits to ionize and so lower the resistance of their respectively included gaseous-discharge tubes as to permit completion of the low potential circuit 15 through the selected tubes and the connected coils.

10. A system for selectively operating a plurality of solenoid coils, comprising in combination with said coils a like plurality of gaseous-discharge tubes, each of said tubes being series connected with one of said coils and the couplets so formed being connected in parallel in a circuit of lower potential than required to ionize said tubes, and means for the selective discharge of predetermined tubes among said plurality of gaseous-discharge tubes thus completing the low potential circuit through the selected tubes and the connected coils.

35 11. A system for selectively operating a plurality of solenoid coils, comprising in combination with said coils a like plurality of gaseous-discharge tubes, each of said tubes being series connected with one of said coils and the couplets so formed being connected in parallel in a circuit 40 of lower potential than required to ionize said tubes, a plurality of high frequency circuits for impressing ionizing surges across said tubes, one of said tubes exclusive of its relay coil being series connected in each of said high frequency circuits, and means for selectively supplying high frequency surges to predetermined high frequency circuits to ionize and so lower the resistance of 45

the respectively included tubes as to permit completion of the low potential circuit through the selected tubes and the connected solenoid coils.

12. A system for selectively operating a plurality of solenoid coils, comprising in combination with said coils a like plurality of gaseous-discharge tubes, each of said tubes being series connected with one of said coils and the couples so formed being connected in parallel in a circuit of lower potential than required to ionize said tubes, a plurality of high frequency circuits for impressing ionizing surges across said tubes, a plurality of condensers, one of said tubes being in series with one of said condensers in each of said high frequency circuits, a high potential circuit, a sparking device in said high potential circuit for generating high frequency surges, and means for selectively transmitting the high frequency surges to predetermined high frequency circuits to ionize and so lower the resistance of the respectively included tubes as to permit completion of the low potential circuit through the selected tubes and the connected solenoid coils. 5 10 15 20

13. A system for selectively operating a plurality of solenoid coils, comprising in combination with said coils a like plurality of gaseous-discharge tubes, each of said tubes being series connected with one of said coils and the couplets so formed being connected in parallel in a circuit of lower potential than required to ionize said tubes, a plurality of high frequency circuits for impressing ionizing surges across said tubes, a plurality of condensers, one of said tubes being in series with one of said condensers in each of said high frequency circuits, a high potential circuit, a switch and a sparking device for generating high frequency surges in each of said high frequency circuits, and means for selectively operating said switches to cause sparking and high frequency surges in predetermined high frequency circuits to ionize and so lower the resistance of the respectively included gaseous-discharge tubes as to permit completion of the low potential circuit through the selected tubes and the connected solenoid coils. 45
